UNITED STATES PATENT OFFICE.

ARTHUR B. WENINK OF MILWAUKEE, WISCONSIN.

DESIGN FOR A REGISTER OR GRILLE.

No. 39,421.

Specification for Design.

Patented July 14, 1908.

Application filed April 7, 1908. Serial No. 425,792. Term of patent 14 years.

To all whom it may concern:

Be it known that I, ARTHUR B. WENINK, a citizen of the United States, residing at Milwaukee, in the county of Milwaukee and State of Wisconsin, have invented a new, original, and ornamental Design for Registers or Grilles, of which the following is a specification, reference being had to the accompanying drawing, forming a part thereof.

The figure is a plan view of a register or grille showing my new design.

I claim:

The ornamental design for a register or grille, as shown.

ARTHUR B. WENINK.
